UNITED STATES PATENT OFFICE

FRED BISZANTZ, OF GALION, OHIO, ASSIGNOR TO THE CENTRAL OHIO STEEL PRODUCTS COMPANY, OF GALION, OHIO, A CORPORATION OF OHIO

LIFTING MECHANISM FOR DUMP BODIES

Application filed February 25, 1930. Serial No. 431,317.

This invention relates to hydraulically actuated dump bodies and particularly to the means whereby the motion of the hydraulically actuated piston is translated into a lifting motion exerted beneath the dump body to tilt it.

One of the objects of the present invention is to provide a lifting mechanism of this character wherein all of the parts of the assembly are disposed above the chassis or frame of the motor truck so that all of the mechanism is easily adapted to all makes of trucks.

Another object is to so connect the body to the hoisting mechanism that no lurching of the truck with the body partly hoisted can pull it away with a consequent rapid downward movement and crash of the body.

A further object is to provide a mechanism of this character which will initially start the lifting movement of the body by means of a relatively short lever compensating for the fact that at this point the greatest work must be performed and the greatest strain is involved and in this connection to provide a mechanism of this character, which after the body is tilted and the center of gravity is shifted toward the rear, the lifting point will shift to accelerate the speed of the lifting and in effect secure the use of a longer lever, this mechanism operating still later to secure a still longer leverage action.

Another object in this connection is to provide a lever and link mechanism acting to lift the body which will prevent any excessive amount of lost motion between the lever and body and which is so constructed that the lever cannot arrive upon a dead center, and in which the travel of the levers is at a uniform speed from start to finish.

Other objects will appear in the course of the following description.

My invention is illustrated in the accompanying drawings, wherein:

Figure 1 is a side elevation of a portion of the chassis or supporting frame of a truck and the body and showing in dotted lines the body lifted to its final tilted position;

Figure 2 is a top plan view of the construction shown in Figure 1;

Figure 3 is a cross section through the lifting cylinder and allied parts.

Referring to these drawings, 10 designates the sub-frame mounted on any suitable or usual truck A. The body is designated 11 and this body is mounted upon a frame consisting of longitudinal elements 12 connected by transverse members 13. The body is operatively pivoted to the truck by means of lugs 14 riveted, bolted or otherwise attached to the elements 12 and extending down below the same and pivotally engaged with the sub-frame 10 as shown in Figure 1, the pivot being designated 15. It will thus be obvious that the body can tilt from the full line position in Figure 1 to the dotted line position.

For the purpose of dumping the body, I provide a hydraulic cylinder 16, one end of which is connected by means of a pipe 17 and suitable connections to a pump such as 70 the rotary pump quite usually used in connection with these hydraulic dumping trucks. Within the cylinder, there is disposed a piston, the piston rod 18 of which extends out over the rear end of the cylinder 75 and is connected to the cross head 19. This cross head extends transversely of the length of the truck. While I do not wish to be limited to the use of any particular means for mounting the cylinder 16 upon the sub-frame 10, I have extended the reduced end 20 of the pipe 17 or an equivalent element through a transverse bar 21, this transverse bar being angularly bent at its ends and being riveted, bolted or otherwise attached to longitudinal plates 22, these plates being suitably braced, the rear ends of these plates 22 being connected to the angular ends of a yoke 23 upon which the cylinder 16 is adapted to seat as shown in Figure 3. The cylinder 16 is held upon the seat of the yoke by means of a hoop 24 which partially surrounds the cylinder and has its ends extended through openings in the yoke 23 and these ends engaged by bolts 25. Fixed shaft 33 extends 90 through plates 22.

The yoke 19 is laterally extended as before stated and has forwardly extended bifurcated extremities 26 to which the end links of chains 27 are pinned as at 28. These 100

chains 27 extend forward and downward and pass over sectors 29. These sectors are connected as by the integral lateral extensions 30 to arms or levers 31, each arm or lever being angularly bent so that the outer end of the arm extends downward and forward when the arm is in its initial or retracted position. Each of these levers is integrally cast with or otherwise connected to a tubular shaft or sleeve 32, these shafts or sleeves being mounted upon a fixed transverse member 33 which constitutes a trunnion for each end of the shaft 32 and engaged in bearings 34 which are attached to the sub-frame elements 10.

The cylinder extends upward and rearward. The ends of the chains are attached to the forward ends of the sectors 29 in any suitable manner. The chains are held from lateral movement on the sectors by means of the lugs 35 or other suitable means. It will be obvious now that when fluid is pumped into the forward end of the cylinder 16, the piston (not shown) therein will force the piston rod outward, forcing the cross head rearward, drawing upon the chains 27, causing a rearward rotation of the sectors 29 and causing the levers 31 to move upward and rearward from the full line position in Figure 1 to the dotted line position in Figure 1.

The levers 31 are preferably formed as illustrated in Figure 2 of two spaced portions connected by spacing elements 36, 37 and 38 which constitute pins co-operating with a link designated generally 39 which will now be described.

There are two links, one on each side of the body. They are connected to the body in any suitable manner, as for instance, to ears 40 mounted upon the beams 12. Each link is pivoted at its upper end to the corresponding ear 40 as by means of the trunnion 41. Each link is widened at its lower end and formed with an angular slot 42, the arms of this slot being acutely angled with relation to each other.

Rearward of this slot, the under face of this link is formed with a seat 43 for the pin 36. The lower wall of the slot is formed with the seats 44 and 45 for the pins 37 and 38 respectively. The rear leg of the slot is formed with the seat 46 for the pin 37 and the forward end of the slot 42 is formed with a seat 47 for the pin 38. The lower end of each link is disposed between the two members forming the lever 31. The pins 37 and 38 are disposed through the slot 42 while the pin 36 is disposed beneath the seat 43 in the initial position of the parts.

In the initial position of the parts, the pin 36 is disposed against the seat 43 of the link. Upon an initial movement of the cross head 19, and a consequent initial movement of the sectors 29, the pins 36 will lift upward on the

links 39, the lifting point being relatively close to the axis of the levers 31 and to the point of application of power to these levers. The upward movement of the levers 31 starts the body upward by lifting against the seats 43 of the links. This gives the effect of a short lever for use at the time when the load is heaviest. After the body is tilted a certain distance and the center of gravity has traveled somewhat toward the rear of the body, the pins 37 reach the seats 46 and the effective length of the levers 31 is thereby increased by the distance between the lifting points or pins. This accelerates the speed of the lifting by the use of a longer lever. Upon a further movement of the parts, the pins 38 come into engagement with the seats 47 and the pins 37 move relatively downward and forward so that eventually the parts have the position shown in dotted lines shown in Figure 1 where the pin 37 is disposed in the seat 45, the pin 37 being disposed against what may be termed the forward wall of the slot at its lower end and the pin 36 being disposed entirely below the link and out of engagement therewith. This acts to still further accelerate the movement of the body as the lifting becomes easier due to the center of gravity of the body moving rearward. At this time, the middle lifting pin 37 as shown in dotted lines in Figure 1 prevents any excessive amount of lost motion between the lever and body and the two lifting pins 37 and 38 acting in unison within the slotted link, prevent the three points, 33, 41 and 38 arriving at a dead center. Upon a downward movement of the body, of course, the reverse action takes place.

At the first part of the movement, the links rest upon the pins 38, until the pins 37 move up into the seats 46. Then these pins 37 take the weight of the body and then the pins 36 take the weight of the body and the parts come to the position shown in Figure 1.

It will be seen that I have provided, therefore, means for operating and engaging the lifting arms or levers 31 with the body, initially at a point inward of the ends of said arms when the arms are in a horizontal position and then as the arms and body rise, shifting the point of operative engagement rearward toward the pivotal axis of the arms. It is also to be noted that I secure a uniform rotation of the tubular shaft or sleeve 32 upon which the arms are mounted by reason of the fact that the curved faces of the sectors 29 are drawn on a true radius from the center of sleeve 32 or axis 33. Consequently the travel of the levers and sectors is at a uniform speed from start to finish with no acceleration in the movement of rotation, but I secure an acceleration of the speed of the lifting by initially using a short lever, then using in effect a longer lever and then using in ef-

fect a still longer lever. Furthermore, it will be seen that as the lever is used, the point of application of the lever to the dumping body shifts toward the center of rotation of the dumping body, that is, the trunnions 15. It is to be noted also that the two lifting points or pins 37 and 38 toward the end of the lever act in unison within the slotted link as shown in dotted lines in Figure 1 to prevent the three points formed by the pins 36, 37 and 38 from arriving at a dead center and that while the final lifting is being done by the pin 38, the middle lifting point formed by the pin 37 prevents any excessive amount of lost motion between the lever and the body.

The mechanism which I have devised keeps all parts of the lifting mechanism above the frame of the motor truck so that the mechanism is easily adapted to all makes of trucks. The body is at all times so connected to the hoisting mechanism that with the body partly hoisted, no lurching of the truck can pull the lifting mechanism away from the body with a consequent release of the part from the lifting body. The link and the lever form a stop preventing any movement to or past the dead center and thus the body will always return to its normal position as soon as the lifting force is released. The lifting levers do not project below the frame. This is particularly desirable as it greatly reduces the number of types of hoists necessarily carried by dealers to fit all makes of trucks. The cylinder, in my construction, is disposed in such position that the force exerted by the piston thereof is in the same general direction as the movement of the body, thus securing high efficiency.

It will be understood, of course, that the pipe 17 is to be connected to a rotary pump as is usual in these hydraulic hoists, that this pump draws fluid through a pipe 17^a from the front of the piston, and forces this fluid into the pipe 17 behind the piston. When the piston arrives at the rear end of the cylinder, it passes the end of pipe 17^a and the movement of the piston stops and if the pump continues to run, fluid will pass through the cylinder and will be again returned to the pump. If the pump be now stopped, the piston rod will settle back a short distance and the body may be held in any position until a valve or valves be shifted to connect the out-put port of the pump with the forward end of the cylinder and the in-put end of the pump with the rear end of the cylinder to permit a reverse motion of the liquid within the cylinder or certain valves operate to permit the return of the piston under the weight of the body.

This mechanism is, therefore, not limited to the use of any particular pumping means or any particular valve means for controlling the flow of fluid into or from the cylinder. Such a valve means, however, is disclosed in my pending application for patent, Serial

No. 431,318, filed on the 25th day of February, 1930.

Obviously many minor changes might be made in the details of construction without departing from the spirit of the invention as defined in the appended claims.

I claim:—

1. In a dumping truck, a supporting frame, a dumping body tiltably on the frame, a shaft on the frame, means for causing rotation of the shaft in one direction at a uniform speed, lifting arms carried by the shaft, means carried by the body and shiftable with relation thereto with which said arms engage, and means for engaging the arms with said means initially at a point inward of the ends of said arms when the arms are in a horizontal position, and then as the arms and body rise, shifting the point of operative engagement away from the pivotal axis of the arms and simultaneously shifting said means toward the pivotal axis of the body.

2. In a dumping truck, a supporting frame, a dumping body tiltably mounted on the frame, a shaft mounted on the frame, means for causing the rotation of the shaft in one direction at a uniform speed, lifting arms carried by the shaft, links pivotally connected to the body and depending therefrom, the lifting arms having operative engagement at all times with said links, and means for operatively engaging the arms with the links, initially at a point inward of the ends of said arms, then as the arms and body rise, shifting the point of engagement of the links and arms away from the pivotal axis of the arms.

3. In a dumping truck, a supporting frame, a dumping body tiltably mounted on the frame, a shaft mounted on the frame, means for causing the rotation of the shaft in one direction, lifting arms carried by the shaft, links pivotally engaged with the dump body for free swinging movement in a vertical plane, each link having a plurality of seats, the arms having a plurality of fulcra successively engaged with said seats as the arms rise, said fulcra being arranged at successively shorter distances from the axis upon which the arms turn.

4. In a dumping truck, a supporting frame, a dumping body tiltable on the frame, a shaft mounted on the frame, means for causing rotation of the shaft in one direction, lifting arms carried by the shaft, links pivotally mounted upon the body and depending therefrom, each of said links having a plurality of seats, each of said arms having a plurality of pins projecting laterally from the arms, and adapted to successively engage said seats as the arms are raised, the pins nearest the center of motion of the arms initially engaging their seats in the links, the pins next in order then successively engaging their seats and the pins adjacent the extremities of the

arms finally engaging their seats in the links as the arms are raised.

5. In a dumping truck, a supporting frame, a dumping body tilttable on the frame, a shaft mounted on the frame, means for causing rotation of the shaft in one direction, lifting arms carried by the shaft, links pivotally mounted upon the body and depending therefrom, each of said links having a plurality of seats, each of said arms having a plurality of pins projecting laterally from the arms, and adapted to successively engage said seats as the arms are raised, the pins nearest the center of motion of the arms initially engaging their seats in the links, the pins next in order then successively engaging their seats and the pins adjacent the extremities of the arms finally engaging their seats in the links as the arms are raised, the final movement of the arms acting to engage two of said pins with two of the seats in the links to thereby prevent the point of engagement of the last named pin with the link from moving to a position of dead center with relation to the pivotal connections of the links and the rotative axis of the arms.

6. In a dumping truck, a supporting frame, a dumping body tilttable on the frame, a shaft on the frame, means for causing the rotation of the shaft, lifting arms carried by the shaft and having a plurality of laterally projecting pins, the pins being arranged in a line from a point adjacent the extremity of each arm toward the center of motion of the arm and links pivotally mounted upon the dump body, each link having an angular slot within which two of said pins are at all times disposed, the slot being formed with seats for said pins, and the exterior wall of the link being formed with a seat for that pin which is nearest the center of rotation of the corresponding arm, said pins successively engaging in said seats as the arms are lifted from the innermost pin to the outermost pin.

45 7. In a dumping truck, a supporting frame, a dumping body tilttable on the frame, a shaft on the frame, means for causing the rotation of the shaft, lifting arms carried by the shaft and having a plurality of laterally projecting pins, the pins being arranged in a line from a point adjacent the extremity of each arm toward the center of motion of the arm and links pivotally mounted upon the dump body, each link having an angular slot within which two of said pins are at all times disposed, the slot being formed with seats for said pins, and the exterior wall of the link being formed with a seat for that pin which is nearest the center of rotation of the corresponding arm, said pins successively engaging in said seats as the arms are lifted from the innermost pin to the outermost pin, each slot being formed with a seat with which the pin adjacent the outermost pin engages when the outermost pin is in engagement with its

seat, and the arms are lifted to their full extent whereby to prevent the link from swinging to a position of dead center.

8. In a dumping truck, a supporting frame, a dump body tilttable on the frame, a shaft carried on the frame and having sectors mounted thereon, flexible elements passing over said sectors, a cylinder having a piston and a piston rod, the piston rod being operatively engaged with said flexible elements to cause a rotation of the sectors and shaft when the piston is forced outward, lifting arms mounted upon the shaft and rotating therewith, and links pivotally mounted upon the dump body and depending therefrom, a plurality of seats formed upon said links, a plurality of pins carried by said arms and adapted to successively engage said seats, the pins being disposed in spaced relation from the extremity of each arm toward the pivotal axis thereof, the innermost pin on each arm first engaging its seat in the respective link and the pins successively engaging their seats as the arms rise.

9. In a dumping truck, a supporting frame, a dump body pivotally mounted upon the frame for tilting movement, a cylinder mounted upon the supporting frame beneath the dump body and having a piston and piston rod, a cross head mounted upon the extremity of the piston rod, the cylinder being disposed in an upward and rearward direction, a shaft mounted upon the supporting frame and carrying sectors of uniform radius, flexible elements connected to said sectors and to the cross head whereby as the cross head moves rearward, the sectors will be rotated, lifting arms mounted upon the shaft and normally extending forward therefrom and provided with a plurality of pins arranged in order from the extremity of each arm toward the center of motion thereof, and links pivotally mounted upon the dump body and having a plurality of seats, one for each of said pins, the pin nearest the shaft on each arm engaging the seat nearest to the pivotal axis of the corresponding link, initially as the arm rises, and the pins successively engaging the successive seats as each arm moves upward toward its highest position whereby to shift the point of operative engagement of the arm with the dump body from a position relatively adjacent the center of motion of the arms to a position relatively further away from the center of motion of the arms.

In testimony whereof I affix my signature.
FRED BISZANTZ.
